UNITED STATES PATENT OFFICE.

HERMANN WITTEK, OF ITZEHOE-SUDE, HOLSTEIN, GERMANY, ASSIGNOR TO PAULINE STOCK, OF ELKHART, INDIANA.

COMBINATION SCAFFOLD AND STEPLADDER.

Application filed July 15, 1926, Serial No. 122,579, and in Germany July 22, 1925.

This invention relates to a combination ladder and scaffold and has as its main object the provision of a structure which may be conveniently and quickly adjusted to either scaffold or step-ladder form, the arrangement being such that a light, simple and effective structure is afforded, which preferably may be folded into a compact form when not in use.

With this object in view my invention consists in certain features of novelty in the construction, combination, and arrangement of parts by which the said object and certain other objects, hereinafter appearing, are effected, all as fully described with reference to the accompanying drawings and more particularly pointed out in the appended claims.

In the said drawings—

Figure 1 is a view of a ladder scaffold embodying my invention and showing the same in its scaffold form;

Figure 2 is a view of the device showing it in its step-ladder form;

Figure 3 is a top plan view of the device showing it in its scaffold form;

Figure 4 is a partial section on the line 4—4 of Figure 3;

Figure 5 is an enlarged partial section on the line 5—5 of Figure 3;

Figure 6 is a side elevation of the portion of the device shown in Figure 5.

Like characters of reference indicate like parts in the several views.

Referring to the drawings 1 designates a ladder element of usual construction, two of which are employed. A platform is provided and comprises two platform sections 2 which are pivotally secured together by hinges 3 and which are also pivotally secured to the upper rungs of respective ladder elements 1 by means of hinges 4, the arrangement being such that the platform sections fold downwardly, as shown in Figure 2, from alined horizontal positions, as shown in Figure 1.

Duplicate pairs of bracing members 5 are disposed at respective sides of the ladder elements and have ends thereof pivotally secured in a usual manner, as designated at 6, to the adjacent side members of respective ladder elements. The other ends of each pair of bracing members 5 are pivotally secured together so that each pair of braces may fold upwardly as shown. The pivot joints

by which each pair of bracing members 5 are pivotally secured together are constructed as follows. See Figures 5 and 6. The adjacent ends of the bracing members 5 are of enlarged disk form, as designated at 7, and rivets 8 pass through the centers of respective pairs of these enlarged disk portions 7 to form these pivot joints. Additional duplicate pairs of bracing members 9 are provided, and each of these pairs of bracing members is pivotally secured together in a usual manner, as designated at 10, and are pivotally secured with respective of respective pairs of bracing members 5 intermediate the ends thereof in a usual manner, as designated at 11.

When the ladder sections 1 are folded together or are disposed in step-ladder form as shown in Figure 2, the bracing members 5 fold upwardly and the bracing members 9 fold with the members 5 downwardly.

When the device is in scaffold form the bracing members 9 of each pair thereof are aligned and serve as tension braces to limit pivotal movement of the bracing members 5 to prevent spreading thereof.

Means is provided, associated with the pivot joints between the bracing members 5 of each pair thereof, for releasably securing the bracing members 5 with the platform sections 2 intermediate the ladder sections 1 and, as shown, consists of the following. Secured on the undersides of respective platform sections 2 at opposite sides thereof and adjacent and extending across the adjoining ends of the platform sections to prevent upward folding of the platform sections are brackets 12. Hand-screws 13 extend through apertures in the enlarged ends 7 of respective pairs of bracing members 5, which apertures register, when the bracing members 5 are in their scaffold positions, as shown in Figures 1, 5, and 6, and are screw-threaded into transverse bores in respective brackets 12 for supporting the platform sections 2 intermediate the ladder elements 1 when the device is in scaffold form.

When it is desired either to fold up the device or to change it to ladder form the screws 13 are removed and the bracing members 5 and 9 are folded.

Cooperating hooks and eyes of usual form, respectively designated at 14 and 15, are mounted on respective side members of respective ladder elements 1 adjacent the

upper ends thereof and serve for releasably securing the ladder elements in step-ladder form, as shown in Figure 2.

It will be observed that the device is easily changed to and from folded form, step-ladder form and scaffold form, that it does not require an unduly heavy construction, and that in either step-ladder or scaffold form it is well adapted to serve the intended purposes and adequately withstand the strains incident to usage.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. In a device of the character described the combination of two ladder elements, a platform comprising two sections pivotally secured together and pivotally secured with respective ladder elements at upwardly disposed points on the ladder elements and adapted to fold downwardly therefrom, and folding bracing means pivotally secured with said ladder elements at downwardly disposed points on the ladder elements and adapted for releasably maintaining said platform sections and ladder elements in the form of a scaffold.

2. In a device of the character described the combination of two ladder elements, a platform comprising two sections pivotally secured together and pivotally secured with respective ladder elements at corresponding upwardly disposed points on the ladder elements and adapted to fold downwardly therefrom, and folding bracing means, including bracing members pivotally secured together and pivotally secured with respective ladder elements at corresponding downwardly disposed points on the ladder elements and adapted to fold upwardly therefrom, and adapted for releasably maintaining said platform sections and ladder elements in the form of a scaffold.

3. In a device of the character described the combination of two ladder elements, a platform comprising two sections pivotally secured together and pivotally secured with respective ladder elements at corresponding upwardly disposed points on the ladder elements and adapted to fold downwardly therefrom, bracing members pivotally secured together and pivotally secured with respective ladder elements at corresponding downwardly disposed points on the ladder elements and adapted to fold upwardly therefrom, means associated with the pivot

point between said bracing members for releasably securing said bracing elements with said platform sections intermediate said ladder elements when said platform sections and ladder elements are in scaffold form, and additional bracing members pivotally secured together and pivotally secured with said first mentioned bracing members below said pivot joint thereof and foldable therewith.

4. In a device of the character described the combination of two ladder elements, a platform comprising two sections pivotally secured together and pivotally secured with respective ladder elements at upwardly disposed points on the ladder elements and adapted to fold downwardly therefrom, duplicate folding bracing means at respective sides of said ladder elements and pivotally secured with said ladder elements at downwardly disposed points on the ladder elements, releasable means for securing said bracing means with said platform sections at respective sides thereof to maintain said ladder elements and platform sections in scaffold form, and releasable means for securing said ladder elements in step-ladder form with said platform sections and bracing means folded.

5. In a device of the character described the combination of two ladder elements, a platform comprising two sections pivotally secured together and pivotally secured with respective ladder elements at corresponding upwardly disposed points on the ladder elements and adapted to fold downwardly therefrom, duplicate pairs of bracing members at respective sides of said ladder elements each pair of which is pivotally secured together and pivotally secured with respective ladder elements at corresponding downwardly disposed points on the ladder elements and adapted to fold upwardly therefrom, means associated with the pivot joints between respective pairs of said bracing members for releasably securing said bracing members to said platform sections at respective sides thereof to maintain said ladder elements and platform sections in scaffold form, additional duplicate pairs of bracing members each pair of which is pivotally secured together and pivotally secured with respective of a respective pair of said first mentioned bracing elements below said pivot joints thereof and foldable therewith, and releasable means adjacent the upper ends of said ladder elements for securing said ladder elements in step-ladder form with said platform sections and bracing members folded.

In witness whereof I affix my signature this first day of July, 1926.

HERMANN WITTEK.
